SPECTACLE FRAME CALIBRATOR

Joseph Santinelli, 36 Bucknell Drive,
Plainview, N.Y. 13137

Filed Feb. 15, 1973, Ser. No. 332,901

Term of patent 14 years

Int. Cl. D10—99

U.S. CL. D52—6 B

FIG. 1 is a front elevational view of a spectacle frame calibrator showing my new design;

FIG. 2 is a right side elevational view thereof, the left side being a mirror image thereof; and

FIG. 3 is a rear elevational view thereof.

I claim:

The ornamental design for a spectacle frame calibrator, substantially as shown and described.
